UNITED STATES PATENT OFFICE.

JOSEPH BURNS, OF OKMULGEE, OKLAHOMA.

TEMPER-SCREW.

1,181,734.

Specification of Letters Patent.

Patented May 2, 1916.

Application filed December 7, 1915. Serial No. 65,510.

To all whom it may concern:

Be it known that I, JOSEPH BURNS, a citizen of the United States, and resident of Okmulgee, in the county of Okmulgee and 5 State of Oklahoma, have invented certain new and useful Improvements in Temper-Screws, of which the following is a specification.

This invention relates to apparatus for 10 drilling deep wells, wherein a temper screw is employed for lengthening the stroke of the tools step by step as the drilling proceeds, so that the bit will strike the bottom of the hole on each down stroke. A bar is 15 swiveled to the lower end of the temper screw, and the drilling cable is suspended from this bar usually by means of a clamp. The screw is rotated and thereby lowered through the split nut carried by the temper 20 screw reins, and the swivel connection with the cable-supporting cross bar permits the screw to be thus turned or paid out without turning either the cable or its support. Much difficulty has resulted from the whirling 25 of the cross bar occasioned by the twisting and untwisting of the cable under its own considerable weight in addition to the very heavy tools suspended thereon. The whirling tendency is much greater with 30 wire cable, now largely used for drilling, than with Manila cable.

The object of this invention is to provide 35 simple and efficient means for holding the swivel bar and the suspended cable and tools from turning or whirling without interfering with the independent rotation of the temper screw. While this result may be variously accomplished, I prefer to form the screw with an axial passage and extend 40 therethrough a holding device which at its lower end is connected to the swivel bar, and at its upper end is in sliding engagement with the screw supporting reins, thereby at all times locking the bar against rotation 45 but without interfering with either the rotation of the temper screw or its vertical movement relatively to its support.

In the accompanying drawings, Figure 1 is a view in side elevation of the improved 50 apparatus in position on a walking beam. Fig. 2 is a view in top plan of a portion of the beam shown in Fig. 1, illustrating the parts immediately associated with the beam. Fig. 3 is an end view of the beam together 55 with the upper portion of the temper screw mechanism. Fig. 4 is a view partly in ele-

vation and partly in vertical section of the temper screw and associated parts. Figs. 5 and 6 are sectional plans on lines 5—5 and 6—6, respectively, of Fig. 4.

Referring to the drawings, 2 designates a walking beam of usual construction having its extremity formed with the customary slot 3 to receive stem 4 of the temper screw reins 5, the latter having flat inner faces as 65 in Fig. 5 to form a slideway for bar 6. The under side of this bar is recessed at 7 to rotatively receive the upper extremity of temper screw 8, Fig. 4, the bar and screw being connected by means presently to be described.

Formed integral with the upper extremity of stem 4 is cross head 9 which is disposed transversely of and is adapted to rest in notch 2' in the top face of the beam. The 75 opposite ends of the bar-like head 9 are disposed downwardly at 10 and slotted vertically at 11 to receive guide pulleys 12 which are journaled therein. Passing over these pulleys, also pulleys 13 located rearwardly 80 on opposite sides of the beam are the lines 14 provided at their rear ends with counterweights 15 and with their forward depending ends secured to the extended extremities of bar 6. By this means a constant upward 85 pull is exerted on the temper screw and when the hold of the split nut 16 carried by the reins is relaxed after the screw has been fully lowered in the operation of drilling, the screw is automatically raised in order to 90 again adjust nut 16 about its lower portion for repeating the operation. Also, by means of this construction the temper screw stem and cross head are held seated on the beam, thereby dispensing with means heretofore 95 provided at the top of the beam for retaining the same in place.

The lower extremity of screw bar 8 is enlarged at 17 to provide a seat for swivel bar 18 from which are suspended links 19 100 for sustaining the cable clamp 20, as is usual in this class of apparatus. Above bar 18 the screw is provided with the usual hand bar 21 for rotating the screw and thereby lowering or paying it out from 105 nut 16 and reins 5 as the drilling proceeds so that on each stroke the tools will strike the bottom of the hole. The screw 8 is tubular from end to end as indicated at 22, and extending therethrough is rod 23 which is 110 squared at its upper end at 23' to fit the squared aperture through the top of bar 6,

the extremity of the rod being provided with nut 24. The lower extremity of the rod is formed with head 25 which is squared at 25' to enter a squared aperture in plate 26 which is removably secured to the depending portion 18' of swivel bar 18. Thus, a non-rotatable connection is provided between the swivel bar and bar 6 slidable between reins 5 whereby the swivel bar is prevented from whirling or rotating under the twisting and untwisting tendency of cable C. As heretofore noted, this tendency is particularly marked with wire cables, and while the swivel bar of a Manila cable clamp 15 may be similarly held, ordinarily the whirling tendency of such cables is not objectionable, so that by simply removing plate 26 the swivel bar is released from its non-rotating connection with the temper screw 20 reins.

The locking connection herein provided in no way interferes with the rotation of the temper screw, the latter being adapted to freely rotate at its lower end between bearing 27 interposed between head 17 and swivel bar 18, also lock bearing 28 arranged between the lower extremity of the screw and the washer-like head 29 located on rod 23 above its enlarged lower end 25. The upper extremity of the screw freely turns in cavity 7 of bar 6.

In the absence of a non-rotatable connection between the swivel bar and temper screw reins, said bar and cable clamp 20 are whirling almost constantly in response to the twisting and untwisting tendency of the wire cable, retarding the operation and rendering it dangerous for the workmen, also subjecting the parts to undue wear. The present invention obviates all these difficulties without interfering with the normal operation of the temper screw.

I claim:

1. The combination of a tubular temper screw, a cable support sustained by and swiveled to the screw, and holding means extending through the tubular screw and connected to the cable support for preventing the latter from turning with the screw.

2. The combination of a tubular temper screw, a screw support in threaded engagement with the screw and through which the latter is adjustable vertically, a cable support suspended by and having a swivel connection with the screw, a holding device extending through the screw and at its lower end connected to the cable support for preventing the latter from rotating with the screw, and a vertically slidable non-rotatable connection between the upper end of the holding device and the screw support.

3. The combination of a tubular temper screw, a support in threaded engagement with the screw and in which the latter is adjustable vertically, a cable support sustained by and having a swivel connection with the screw, a rod extending through the screw, a device slidable in the temper screw support and held by the latter against rotation and with the upper end of said rod secured to said device, and means connected to the lower end of said rod and secured to the cable support for holding the latter against rotation.

4. The combination of a tubular temper screw, a temper screw support comprising parallel reins and a nut carried by the reins through which the screw operates, a device slidable vertically between the reins and held by the latter against rotation, the temper screw rotatably secured at its upper end to said device, a rod extending through the temper screw and about which the latter is adapted to rotate with the upper end of said rod held against rotation by said slidable device, a cable support sustained by and having a swivel connection with the lower end of the screw, and means connected to the lower end of said rod and secured to the cable support for holding the latter against rotation.

In testimony whereof I affix my signature in presence of two witnesses.

JOSEPH BURNS.
